(57) CLAIM

I claim the ornamental design for a multiparty earbuds, as shown and described.

DESCRIPTION

FIG. 1 is a perspective top view of multiparty earbuds showing my new design, the cord is drawn broken away for indeterminate length;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof; and,

FIG. 8 is a perspective view illustrating an exemplary application of the multiparty earbuds.

The broken lines illustrating two users, an electronic music player, and an exemplary second listening device illustrated in FIG. 8 form no part of the claimed design.
